Patented Jan. 8, 1918.

2 SHEETS—SHEET 2.

UNITED STATES PATENT OFFICE.

SAMUEL A. WILLIAMS, OF LOS ANGELES, CALIFORNIA.

MECHANICAL MOVEMENT.

1,252,758.

Specification of Letters Patent.

Patented Jan. 8, 1918.

Application filed February 3, 1916. Serial No. 75,944.

To all whom it may concern:

Be it known that I, SAMUEL A. WILLIAMS, a citizen of the United States, residing at Los Angeles, in the county of Los Angeles, 5 State of California, have invented a new and useful Mechanical Movement, of which the following is a specification.

The invention relates to railroad crossing signals, such as are used where highways 10 cross railroad tracks. The principal object of the invention is to provide an audible and visible signal which will warn highway traffic of the approach of a train.

A further object of my invention is to 15 provide a signal that will be very conspicuous and which will be operated by a simple mechanism.

The railroads at the present time have adopted a stationary warning signal consisting of two sign-boards set at 45° with the vertical and suitably inscribed. A further object of my invention is to provide a signal which, at rest, will look exactly like the standard sign-board now in use so that 25 in case of accident to the mechanism the signal will be exactly equivalent to such standard sign-board.

The invention consists broadly of a pair of sign-boards set at right angles to each 30 other and provided with means for oscillating them upon the approach of a train. It consists further of an illuminated pendulum swinging a red light below said sign-boards upon the approach of a train, and it consists further in the addition of a gong or 35 other audible device actuated simultaneously with the sign-boards.

In the drawings, which are for illustrative purposes only:

40 Fig. 1 is a side elevation of the signal as mounted on suitable supporting structure.

Fig. 2 is a partial section on an enlarged scale on a plane represented by the line x^2-x^2 of Fig. 1.

45 Fig. 3 is an enlarged section on the same plane of the inclosing case and the mechanism contained therein.

Fig. 4 is an elevation, partly in section, on a plane represented by the line x^4-x^4 of 50 Fig. 3.

Fig. 5 is a diagram of connections.

In these drawings, a supporting pole 11 is supplied to which bracket arms 12 are

secured by means of U-bolts, these bracket arms being partly supported by braces 14 55 which are also secured to the pole by suitable U-bolts. The signal itself is mounted on the arms 12 and consists of a case 20 having a removable bottom 21 and a hand hole cover 22 in one side thereof. Mounted 60 in suitable bearings 23 in either side of the case 20 is a hollow main shaft 24, this shaft projecting out at either side of the case 20 and having hubs 25 rigidly secured at either end thereof. Secured by means of bolts 26, 65 to the hubs 25, are a pair of sign-boards 27 arranged in the form of a cross and having suitable warning legends painted thereon. Secured outside the hubs 25 are sockets containing a pair of incandescent lamps 28. 70 Pendulum arms 29 are secured in the shaft 24, these pendulum arms consisting of hollow pipe and extending down inside the sign boards 27 to a Y 30, this Y being connected through a short length of pipe 31 with a 75 pendulum 32, this pendulum consisting of an inclosing casting 33 having face plates 34 secured thereon, each of these face plates having an opening covered by a lens 35 preferably formed of colored glass, each of these 80 lenses being shielded by a shadow box 36. Located inside the pendulum 32 are a pair of incandescent lamps 37. The lamps 37 are provided with suitable wiring, not shown, which runs up through the pipe 31 and arms 29, and the interior of the shaft 24 being taken out through the opening 38 in the shaft 24. The lamps 28 are also connected to suitable wiring, not shown, which runs back through the shaft 24 and outwardly 90 through the opening 38. Secured on the shaft 24 is a fiber spool 39, this spool having an opening therein which registers with the opening 38, and through which the wires for the lamps 28 and 37 are brought. These 95 wires are coiled around the spool 39 several times, being then taken to binding posts 41 which are secured on a slate or porcelain slab fixed to the upper wall of the case 20, as shown in Fig. 4. The object of the spool 100 39 is to provide some slack so that current can be supplied to the lamps 28 and 37 as the shaft 24 turns. Rigidly secured to the shaft 24 is a crank 42, this crank having a crank pin 42' on which one end of a connecting rod 43 is pivoted. The other end

of the connecting rod 43 is pivoted on a pin 44 carried by a crank disk 45. The crank disk 45 is rigidly secured to a worm gear shaft 46. Formed on the exterior of the 5 crank disk 45 are a succession of ratchet teeth 47. A striking lever 48 extends out of the ratchet teeth 47 and is provided with a hooked end 49 coöperating therewith. The lever 48 is pivoted on a pin 50 secured on 10 an extension 51 formed on the bottom 21. The bottom 21 forms a base for the mechanism. Rigidly secured on the lever 48 is a striking rod 52, this rod extending downwardly through an opening 53 in the base 15 and inside a gong 54 which is secured by means of a bolt 55 to a boss 56 formed on the underside of the bottom 21. A tension spring 57 is secured at 58 to the bottom 21, the other end being secured to a pin 59 se- 20 cured in the lever 48. Located on and surrounding the shaft 46 is a quill 60, this quill turning freely on the shaft 46 and having a worm gear 61 secured thereon. The quill 60 turns in bearings 62 formed on the bot- 25 tom 21, ball bearings being supplied, as shown, if desired. Rigidly secured on one of the bearings 62, by means of screws 63, is a magnet case 64 which contains a coil 65. Turning inside the magnet case 64, and 30 secured to the quill 60, is an armature 66, and secured to the shaft 46 is a keeper 67. The armature 66 is formed of non-magnetic material having a section of magnetic material 68 inserted therein. A worm gear 70 35 is formed on a shaft 71, this shaft being carried in bearings 72 formed on the bottom 21 and being connected through coupling 72 with a motor 74. One of the binding posts 41 is connected externally through a wire 40 100 with one terminal of a battery 101 the other terminal of which is connected through a wire 102 with a switch or relay 103 which is in turn connected through a wire 104 with the other binding post 41. Internally one 45 of the binding posts 41 is connected through a wire 105 with one terminal of the coil 65, the other terminal of which is connected directly to one terminal of the motor 74. The other terminal of the motor 74 is connected 50 through a wire 106 with the other binding post 41.

The signal is normally in the position shown in Fig. 1. In this position the magnet 65 is not energized and there is no adhesion between the armature 66 and the keeper 67, so that the shaft 46 is free to turn inside the quill 60, and the sign-boards are free to assume their normal position as shown in Fig. 1.

60 Whenever it is desired to actuate the signal, which may be done automatically by any of the well known means, or which may be done by a gateman, or other person, employed for the purpose, current is supplied

to the binding posts 41, this current lighting 65 the lamps 28 and 37 and causing the pendulum 32 to be illuminated, this light appearing through the lenses 35 which are preferably formed of red glass.

Current is at the same time supplied to 70 the motor 74, and the motor starts to rotate, turning the gear 61 through the worm 70 and thus turning the quill 60 and the armature 66. The magnet 65 being simultaneously energized with the motor 74, the armature 66 75 becomes energized.

The armature 66 attracts and grips the keeper 67 which is formed of steel or cast iron. This results in locking the armature 66 and the keeper 67 together, thus causing 80 the quill 60 and the shaft 46 to rotate together. As the shaft 46 rotates the pin 44 moves in a small circle, thus pulling one end of the connecting rod 43 back and forth. The crank 42 has a larger radius than that 85 of the pin 44, so that the pin 42' is pulled back and forth through an arc of approximately 90 degrees. This back and forth movement throws the sign-boards 27 alternately into the vertical position and throws 90 the pendulum 32 back and forth, thus furnishing an unmistakable visible warning signal. At the same time the rotation of the crank disk 45 causes the gong 54 to ring, the teeth 47 alternately lifting and dropping the 95 end 49 of the lever 48, the movement of this lever causing a clapper on the end of the rod 52 to strike sharply on the inside of the gong, thereby causing it to emit sound. This movement of the sign-boards 27, the illumination 100 of the lamps 28 and 37, and the sounding of the gong 54 continues as long as current is supplied to the binding posts 41. Whenever current is shut off from the binding posts 41, the lights go out, and the motor 105 stops. There is, however, considerable inertia in moving mechanism of this kind, and the motor may continue to rotate, and the sign-boards to move for a considerable time, after the current is shut off. The cutting off 110 of the current from the binding posts 41 also cuts off current from the magnet 65, and releases the magnetic gripping action between the armature 66 and the keeper 67, so that the sign-boards 27 are mechanically disconnected 115 from the motor. The result is that these sign-boards come to rest in the position shown in Fig. 1, the weight of the pendulum 32 being sufficient to draw them back to this position as soon as the armature 66 disconnects from the keeper 67.

I claim as my invention:

A mechanism for actuating a railroad signal comprising a main shaft; a crank secured to said shaft; a crank pin on said crank; a connecting rod pivoted at one end on said crank pin; a crank disk; a pin secured in said crank disk and having the

other end of said connecting rod pivoted thereon; a driving shaft secured in said crank disk; a quill surrounding said shaft; a motor; gearing permanently connecting said motor with said quill; a clutch so arranged as to lock said quill and said driving shaft together; and electromagnetic means

for locking said quill and said clutch together.

In testimony whereof, I have hereunto set my hand at Los Angeles, California, this 26th day of January, 1916.

SAMUEL A. WILLIAMS.
